US00D345846S

United States Patent [19]

Przytulla et al.

[11] Patent Number: Des. 345,846
[45] Date of Patent: ** Apr. 5, 1994

[54] DRUM

[75] Inventors: Dietmar Przytulla, Kerpen; Maerten Burgdorf, Heimerzheim, both of Fed. Rep. of Germany

[73] Assignee: Mauser-Werke GmbH, Brühl, Fed. Rep. of Germany

[**] Term: 14 Years

[21] Appl. No.: 566,571

[22] Filed: Aug. 13, 1990

[30] Foreign Application Priority Data

[57] CLAIM

The ornamental design for a drum, as shown and described.

DESCRIPTION

FIG. 1 is a perspective view of the drum according to a first embodiment of the design;
FIG. 2 is a side view of the drum according to the first embodiment;
FIG. 3 is a front view of the drum according to the first embodiment;
FIG. 4 is a rear view of the drum according to the first embodiment;
FIG. 5 is a top view of the drum according to the first embodiment;
FIG. 6 is a bottom view of the drum according to the first embodiment;
FIG. 7 is a fragmentary perspective view of the top of the first embodiment;
FIG. 8 is a perspective view of the drum according to a second embodiment of the design, the top view being the same as the first embodiment;
FIG. 9 is a side view of the drum according to the second embodiment;
FIG. 10 is a front view of the drum according to the second embodiment;
FIG. 11 is a rear view of the drum according to the second embodiment;
FIG. 12 is a bottom view of the drum according to the second embodiment;
FIG. 13 is a perspective view of the drum according to a third embodiment of the design;
FIG. 14 is a front view of the third embodiment of the design;
FIG. 15 is a bottom view of the third embodiment of the design;
FIG. 16 is a top view of the drum top according to a fourth embodiment of the design as used with either of the drums of FIGS. 1, 8 or 13;
FIG. 17 is a fragmentary perspective view of the fourth embodiment; and,
FIG. 18 is a fragmentary perspective view of the top of a fifth embodiment as used with the drum of FIGS. 1, 8 or 13.
